SCRATCHING POST

Daniel D. Yoder, Seattle, Wash.

Application January 29, 1934, Serial No. 708,771

3 Claims. (Cl. 119—1)

This invention relates to scratching posts and has for its object to provide a device of that character suitable as an article of furniture and designed especially for use by domestic animals, such as cats or other house pets, on which they may scratch to dull their claws and to obtain a certain amount of exercise.

Explanatory to the invention, it will be here stated that pet cats that are kept indoors for the most part of the time, do not have the proper kind or sufficient exercise to keep their claws from growing long and sharp. Therefore, it is the general rule that cats which are kept in apartment houses or city dwellings will endeavor to exercise and trim their claws by scratching on furniture, rugs or other articles which will provide the necessary traction. This is not only injurious to the furnishings and furniture but also is unsatisfactory to the cat.

In view of the above it has been the object of the present invention to provide a scratching post of an attractive and ornamental character and containing a substance such as catnip or other substance having an odor attractive to cats, so that they will be enticed thereto and will confine their scratching operations to the one object; the post being covered with a material into which they can sink their claws to afford the necessary traction for exercising the leg and toe muscles and for breaking or wearing off their claws in the manner to which they are accustomed if permitted to run freely out of doors.

It is also an object of the invention to provide a post of the above kind having a covering material that is easily and readily removable permitting it to be replaced when it becomes worn.

Other objects reside in the details of construction and combination of parts, as will hereinafter be fully described.

In accomplishing these objects of the invention, I have provided the improved details of construction, the preferred forms of which are illustrated in the accompanying drawing wherein—

Fig. 1 is a perspective view illustrating the construction and use of a scratching post embodied by the present invention.

Fig. 2 is a perspective view of the parts of the post in disassembled relationship.

Fig. 3 is a horizontal, cross sectional view of the post, particularly illustrating the pockets in the post for the catnip and manner of applying the fabric about the post.

Referring more in detail to the drawing—

In the preferred form of construction, the device comprises a flat base block 1 on which a

post 2 is vertically mounted. The base block in a practical form is approximately twelve inches square and the post is approximately three and one-half inches square in cross section and two feet long. However, it is to be understood that these dimensions may be varied as desired without departing from the spirit of the invention.

The post is fixedly supported upon the base by means best illustrated in Fig. 2, comprising a dowel pin 3 that is fitted in the base of the post with an end extended therefrom and designed to be fitted within an opening 4 centrally of the base member 1. It is understood, however, that various other means might be employed for mounting the post with satisfactory results.

In three side surfaces of the post are pockets 5, as seen best in Fig. 3, containing packs 6 of the foliage of catnip or any other suitable material having an odor that will be attractive to cats. These packs are of cloth and are secured in the pockets by tacks 7 driven through their ends to hold them securely within the pockets. Extending the length of the post along one side is a groove 8 and wrapped about the post from end to end and over the top is a fabric covering 9, preferably this would be a piece of carpeting material which has its ends located in the groove 8 and held securely therein by the application of a thin wooden strip wedged into the groove between the ends of the covering strip. Tacks 11 may be applied if needed to hold the carpet in place at upper and lower ends of the post.

With the device so constructed, it may be conveniently moved about the home to any suitable place and will, by reason of its appearance, serve as an ornamental piece of furniture. Cats will be attracted by the odor given off by the catnip packs and will scratch on the fabric covering for exercise and for dulling their claws. When the fabric becomes worn it may be removed by withdrawing the strip 10 and the tacks 11 and may be easily and readily replaced by a new piece.

It is to be understood that the post might vary in its details of construction and design without departing from the spirit of the invention. For instance, it may be round or hexagonal or various other forms.

Having thus described my invention, what I claim as new therein and desire to secure by Letters Patent is—

1. A device of the character described comprising a base and a standard fixed thereon having a fabric covering, and containers beneath the fabric covering for a substance attractive to cats.
2. A device of the character described comprising

ing a base, a standard on the base having pockets formed therein containing a substance having an odor attractive to cats, and a fabric covering on the standard.

- 5 3. A device of the character described comprising a base, a standard erected thereon; said standard having a key slot longitudinally thereof,

and having pockets in some of its side walls, means in said pockets enclosing substance having an odor attractive to cats, and a fabric strip covering said standard and having its ends disposed in said key slot and a key applied to said slot to hold the strip in place.
